UNITED STATES PATENT OFFICE.

CHARLES W. LIND AND CHARLES N. SILVER, OF BELOIT, WISCONSIN.

DESIGN FOR A FLOWER-STAND.

SPECIFICATION forming part of Design No. 35,627, dated January 28, 1902.

Application filed December 27, 1901. Serial No. 87,494. Term of patent 14 years.

To all whom it may concern:

Be it known that we, CHARLES W. LIND and CHARLES N. SILVER, citizens of the United States, residing at Beloit, in the county of Rock and State of Wisconsin, have invented a new and useful Design for a Flower-Stand, of which the following is a specification.

This invention relates to a new and original design for a flower-stand; and the essential features reside in the design as illustrated in the accompanying drawing, wherein a perspective view of the stand is presented.

The design is characterized by a table 1, of circular form, having a plurality of supplemental circular rests 2 thereon, and from the center of said table a cylindrical center post 3 depends and terminates at its lower end in a rounded knob 4 and circumferential beads 5. The table 1 is surrounded by a guard 6, extending above and below the same and comprising diagonally-disposed intersecting bars 7, with the upper and lower ends formed with inturned connected scrolls 8. From the under side of the table bracket-scrolls 9 extend downwardly and inwardly to an intermediate portion of the center post 3 and have auxiliary scrolls 10 secured thereto, and also having portions thereof fastened to the cen-

ter post above the point of engagement with said post of the scrolls 9, the intersecting portions of the scrolls 9 and 10 having interposed inclined bars 10^a. The lower out-turned terminals 11 of the scrolls 9 are fastened to radial bars 12, extending horizontally outwardly from the center post, and also connected to said bars 12 are the upper out-turned terminals 13 of scroll-legs 14, having lower inturned members 15, with scroll-feet 16. The scroll-legs 14 also have inturned supporting-scrolls 17, secured to the lower part of the center post, and parts of the members 15 and scrolls 17 are connected and at the points of connection have interposed inclined bars 18.

Having thus described the invention, what is claimed as new is—

The design for a flower-stand, as herein shown and described.

In testimony whereof we affix our signatures in presence of two witnesses.

CHARLES W. LIND.
C. N. SILVER.
